(57) **CLAIM**

The ornamental design for an accessory holder, as shown and described.

DESCRIPTION

FIG. 1 is a perspective view of an accessory holder showing my new design as worn on the user's thigh;
FIG. 2 perspective view thereof in a closed position;
FIG. 3 is a perspective view thereof in an open position;
FIG. 4 is top plan view thereof in an open position;
FIG. 5 is a bottom plan view thereof in an open position;
FIG. 6 is a left side elevational view thereof;
FIG. 7 is a right side elevational view thereof;
FIG. 8 is an end elevational view thereof;
FIG. 9 is an opposite end elevational view thereof;
FIG. 10 is an enlarged cross-sectional view shown along lines 10—10 of FIG. 4; and,
FIG. 11 is an enlarged cross-sectional view shown along lines 11—11 of FIG. 5.
The portions shown in broken lines are included for illustrative purpose only and form no part of the claimed design.
